DESIGN FOR A RADIO CASING

Robert D. Budlong, Chicago, Ill., assignor to
Zenith Radio Corporation, Chicago, Ill., a cor-
poration of Illinois

Application February 7, 1941, Serial No. 98,836

Term of patent 14 years

To all whom it may concern:

Be it known that I, Robert D. Budlong, a citizen of the United States, residing at Chicago, in the county of Cook and State of Illinois, have invented a new, original, and ornamental Design for a Radio Casing, of which the following is a specification, reference being had to the accompanying drawing, forming part thereof.

Figure 1 is a front perspective view of a radio casing, showing my new design; and

Figure 2 is a broken vertical sectional view taken through the middle of the front of said casing.

I claim:

The ornamental design for a radio casing, as shown.

ROBERT D. BUDLONG.
